UNITED STATES PATENT OFFICE.

ALONZO A. WARNER, OF NEW BRITAIN, CONNECTICUT, ASSIGNOR TO LANDERS, FRARY & CLARK, OF NEW BRITAIN, CONNECTICUT, A CORPORATION OF CONNECTICUT.

MIXING-MACHINE.

1,137,037.

Specification of Letters Patent. Patented Apr. 27, 1915.

Application filed March 25, 1914. Serial No. 827,227.

To all whom it may concern:

Be it known that I, ALONZO A. WARNER, a citizen of the United States, and a resident of New Britain, in the county of Hartford, 5 State of Connecticut, have invented certain new and useful Improvements in Mixing-Machines, of which the following is a specification.

This invention relates particularly to a 10 machine for mixing together various ingredients, as for instance in the making of salad dressings, etc., and has for its object to produce a device of this sort having features of novelty and advantage, and particularly to provide means for very thoroughly mixing the ingredients and keeping them always in the mixing zone.

In the embodiment of the invention selected for illustration, Figure 1 is a side 20 view. Fig. 2 is a top view. Fig. 3 is a central vertical section. Fig. 4 is a detail of the attachment of the beater to its shaft.

In the drawings, *a* denotes the base which is preferably provided with a screw clamp 25 in order that it may be attached to a table. *b* is the bowl supported on the base, and *c* the cover for the bowl which is engaged by the nuts *d* at the end of the tie rods *e* which are connected with the base and serve to 30 bind the bowl between the cover and the base and so assemble these three parts together. The beater driving mechanism, indicated generally at *f*, is mounted on the cover. The cover is also provided with an aperture *g* 35 through which ingredients may be introduced into the bowl, and with a funnel *h* provided with a stopcock *i* through which oil or other liquids may be fed in such quantities and at such a rate as may be desired.

40 *2* denotes a standard secured to the cover and having a lateral arm *3* from which extends a lateral shaft *4* upon which is mounted the main driving member *5*. *6* is a handle also mounted on this shaft and having driving 45 connection with the head of the main driving member *5*, and held in position by the nut *7*. This main driving member comprises two bevel gears, one *10* at its periphery, and the other *11* near its center. The last mentioned gear meshes with a bevel pinion *12* secured to a shaft *13* which passes through the lateral arm *3* and has secured to its lower end a driving head *14*.

Having a bearing in an aperture in the 55 base of the standard *2* is a second bevel pin-

ion *20* which meshes with the bevel gear *10* at the periphery of the main driving member. This pinion *20* is formed at the end of a hollow sleeve *21* through which passes the beater shaft *22*, the end of which is fitted 60 into a socket in the driving head *14* at one side of its center, forming an eccentric connection of the beater shaft to the driving head. Secured to the beater shaft as by a set screw *23* is a sleeve *24* having a squared 65 lower end *25* which fits within the squared upper end of the sleeve *21*, forming a driving connection between the pinion *20* and the beater shaft. This driving connection can be other than that here illustrated and 70 described.

From a study of the mechanism above described it will be seen that the beater is caused to travel around the interior of the bowl, and at the same time is rotated upon 75 its own axis, and the greatest width of the beater is at least equal to and preferably slightly greater than one half the diameter of the bowl, the consequent result being that the ingredients cannot get away from the 80 beater but are always and continuously being mixed together by this compound action of the beater.

The bottom of the bowl is concaved as indicated at *25*, and the end of the beater is curved to fit the concavity of the bowl as clearly shown at *26* in Fig. 4. The beater also has a slip connection with the shaft through the pin *30* in the shaft working in the slot *31* in the beater, with the result that 85 the beater always rests on the bottom of the bowl. The bottom and side blades of the beater are deeply serrated as indicated at *33*, producing a structure which somewhat approximates the tines of a fork, greatly facilitating the complete and thorough mixture 90 of ingredients.

I am aware that the invention as here described is susceptible of various changes and alterations without departing from the spirit 100 of the invention.

I claim as my invention:

1. In a device of the character described, a bowl, a beater within said bowl, and a beater shaft, driving connections for said shaft, a non-revolvble bearing for said shaft, and means engaging said shaft at the opposite side of said bearing from said beater to cause said beater to move in a 105 circular path within said bowl.

2. In a device of the character described, a bowl, a beater located therein, a beater shaft and a non-revolute bearing therefor, a driving head and means for rotating it, an eccentric connection between said driving head and beater shaft, a gear secured to said shaft at a point between said driving head and beater, and means for rotating said gear. 5
- 10 3. In a device of the character described, a bowl, a beater therein, a beater shaft, a driving head, the end of said shaft terminating adjacent to said head and eccentrically connected therewith, a pinion having driving connection with said beater shaft between said head and beater, a second pinion having driving connection with said head, and a main driving member having separate gears meshing with said pinions. 15
- 20 4. In a device of the character described, a bowl, a cover therefor, a hollow sleeve fitted in an aperture in said cover and provided with a pinion at its upper end, a beater within the bowl, a beater shaft extending through said sleeve, a tapering polygonal member secured to the beater shaft and fitting within the similarly shaped upper end of said hollow sleeve, a driving head, and an eccentric connection between 25
- said head and the upper end of said beater shaft, a pinion connected with said driving head, and means for operating said pinions. 30
5. In a device of the character described, a bowl, a cover therefor, a standard mounted on the cover and having a base and a laterally extending arm, a driving gear supported on a hollow sleeve in said base, a vertical shaft extending through said lateral arm, a gear secured to the upper end of said shaft, and a driving head to the lower end 35 thereof, a laterally extending shaft mounted in the end of said arm, a driving member mounted thereon and provided with gears meshing with the two first mentioned gears, a handle slideable on said shaft, interengaging parts on said handle and driving member, a nut threaded onto said shaft to hold the last mentioned parts in engagement, a beater within the bowl, a beater shaft extending through said hollow sleeve and having its upper end eccentrically connected 40 with said driving head, and means secured to said beater shaft and having a driving connection with the first mentioned gear. 45
- 50 ALONZO A. WARNER.
